C. H. T. HAGELSTEIN.
BUTTONHOLE FINISHING MACHINE.
APPLICATION FILED MAY 28, 1913.

1,124,894.

Patented Jan. 12, 1915.

UNITED STATES PATENT OFFICE.

CHRISTIAN H. T. HAGELSTEIN, OF BOSTON, MASSACHUSETTS, ASSIGNOR TO THE REECE
BUTTON HOLE MACHINE COMPANY, OF BOSTON, MASSACHUSETTS, A CORPORATION
OF MAINE.

BUTTONHOLE-FINISHING MACHINE.

1,124,894.

Specification of Letters Patent. Patented Jan. 12, 1915.

Application filed May 28, 1913. Serial No. 770,317.

To all whom it may concern:

Be it known that I, CHRISTIAN H. T. HAGELSTEIN, a citizen of the United States, residing at Boston, county of Suffolk, State 5 of Massachusetts, have invented an Improvement in Buttonhole-Finishing Machines, of which the following description, in connection with the accompanying drawing, is a specification, like characters on the 10 drawing representing like parts.

This invention relates to sewing machines of that type that are used for finishing buttonholes. These machines commonly comprise a bender for making bends in the 15 work, a horizontally reciprocating eye-pointed needle which at alternate thrusts passes through the bent portion of the work, and a shuttle which co-operates with the needle in forming the stitch. A machine of this 20 type is shown in my Patent No. 1,009,408 dated November 21, 1911, and in order to illustrate the present invention I have shown it as it would be applied to a sewing machine similar to that disclosed in my aforesaid 25 patent. I wish to state, however, that the features of the present invention are applicable to other types of sewing machine than that above referred to.

The object of the present invention is to 30 provide improvements in sewing machines of the above type, all as will be more fully hereinafter described and then pointed out in the appended claims.

Referring now to the drawings wherein 35 I have illustrated a selected embodiment of the invention, Figure 1 is a side view of a sewing machine such as is illustrated in my aforesaid Patent No. 1,009,408, having my improvements applied thereto. Fig. 2 is 40 a top plan view of the shuttle. Fig. 3 is a section through the shuttle on the line $x-x$, Fig. 2.

The machine shown in Fig. 1 and in connection with which I have chosen to illustrate my improvements is similar in its 45 principal features to the machine shown in my aforesaid Patent No. 1,009,408, and as the present improvements relate to detail features of the machine rather than to the 50 entire organization, I will not describe the entire machine in detail but will simply give a sufficient description thereof to enable any one skilled in the art to clearly understand the present improvements.

The machine herein shown comprises the 55 base frame 1 from which rises the overhanging arm 23 that carries the presser foot and bender mechanism and the operative parts therefor. The presser foot is shown at 25 and it is depressed by means of a lever 60 21 pivoted at 22 to the arm 23, and acted upon by springs 24 which normally tend to hold it elevated. The bender is shown at 37 and it is actuated from a rock shaft 61 carried in the overhanging arm 65 by means of a connecting rod 58, that in turn is operated from the main shaft 5, all as illustrated in said Patent No. 1,009,408. This bender 37 operates to intermittently 70 bend the work into a groove 48 formed in a throat plate 45. The stitching is performed by the usual eye-pointed needle 97 which is reciprocated beneath the bed plate by any suitable mechanism acting in conjunction with the shuttle 120 that is sustained 75 by a shuttle carrier 4 mounted on a vertical spindle 121 that is operated from the driving shaft by any usual mechanism, such, for instance, as shown in my prior Patent No. 1,009,408. The parts thus far described are 80 or may be as illustrated in said patent and form no part of my invention.

The driving shaft 5 is operated from a loose pulley 8 by means of a clutch which is similar to that illustrated in U. S. patent 85 to Reece No. 367,063 dated July 26, 1887.

The shuttle carrier 4 rotates in a block 61 which is recessed to receive said shuttle carrier and which is secured to the bed frame 1 all as set forth in said before-mentioned patent. This shuttle carrier is provided with the horn 7 which engages one end of the shuttle and with the portion 8 that engages the other end of the shuttle, said portion 8 having an extended needle supporting portion 9 adjacent the hook 125 of the shuttle 90 and on which the point of the needle is supported after it has passed through the bend in the work and while the shuttle hook 125 enters the loop of needle thread. This support 9 prevents any accidental displacement 100 of the needle during the bending of the work which might interfere with the proper function of the shuttle hook. In Fig. 3 the needle 97 is shown in dotted lines and the 105 operation of the support 9 will be readily apparent.

The shuttle thread τ is delivered from the

shuttle and extends in the direction shown in Fig. 3 toward the point where it leads into the work. This shuttle thread is taken from a bobbin 50 which is loosely received 5 in a recess formed in the shuttle, the thread extending from the bobbin around the tension device 51 and thence out through an eye 52 in the side of the shuttle. The bobbin is loosely retained in its recess in the shuttle 10 and of course it rotates around its own axis in said recess as the thread is drawn therefrom. It sometimes happens that during the rapid operation of the machine the bobbin will overrun thus giving up slack thread 15 and if this occurs such slack thread is apt to get caught on the point and become entangled with the hook 125 of the shuttle. If this occurs the thread is very likely to become broken. In order to prevent this from 20 happening I have provided a thread support which overlies the needle support 9 and which extends substantially to the path in which the shuttle point 125 operates, said thread support operating to hold the shuttle 25 thread *t* out of the path of the shuttle point 125 thus preventing it from becoming entangled with said point. This thread support is shown at 15 and is in the form of a plate or shelf which extends parallel to the 30 needle support 9, which is situated above and is separated therefrom thereby presenting the throat 16 in which the point of the needle operates. This thread support 15 may be sustained in any suitable way. I 35 have herein shown the needle support 9 as provided with the wall or portion 17 which may be integral therewith and on which the thread support 15 is secured. I may, if desired, make the thread support 15, the wall 40 17 and the needle support 9 all integral with each other and integral with the shuttle carrier 4. The outer edge 18 of the thread support is curved and follows the curvature of the path of movement of the shuttle point 45 125, said edge 18 coming closely adjacent to the said path of movement. The shuttle thread *t* will, therefore, be supported clear up to the path of movement of the shuttle point and said thread cannot by any possibility become caught by or entangled in said 50 shuttle point.

40 is the usual cover plate that covers the shuttle carrier. The edge 41 of this plate

engages the undercut wall 42 on the bed plate and the cover is held in place by a 55 locking member 45 mounted on a stud 46 which has secured thereto a handle 56 extending through a slot 57 in the machine frame. The locking head 45 is slabbed off at 49 so that when the handle is turned into 60 the dotted line position Fig. 4, the cover plate is unlocked. When the handle is in the full line position, however, the cover plate is locked in position by the portion 43 overlapping the edge of the cover plate. 65

While I have described one embodiment of my invention, I do not wish to be limited to the constructional details shown.

Having fully described my invention, what I claim as new and desire to secure by 70 Letters Patent is:—

1. In a sewing machine, the combination with a throat plate having a bending groove, of a bender coöperating with said groove, a horizontally reciprocating needle, an oscillatory shuttle carrier provided with a needle support, a shuttle sustained by said shuttle carrier and provided with a shuttle hook and a shuttle-thread support situated above the needle support and having its edge 75 situated closely adjacent the shuttle hook, said support constituting a support for the shuttle thread and operating to prevent the latter from becoming entangled with the shuttle hook. 85

2. In a sewing machine, the combination with a throat plate having a bending groove, of a bender coöperating with said groove, a horizontally reciprocating needle, an oscillatory shuttle carrier provided with a needle support, a shuttle sustained by said shuttle carrier and provided with a shuttle hook and a flat shuttle-thread support situated above the needle support and spaced therefrom and operating to prevent the shuttle thread from 90 becoming entangled with the point of the shuttle, said shuttle-thread support extending substantially to the path of movement of said shuttle hook. 95

In testimony whereof, I have signed my 100 name to this specification, in the presence of two subscribing witnesses.

CHRISTIAN H. T. HAGELSTEIN.
